ATTORNEY

UNITED STATES PATENT OFFICE

THOMAS J. BIGHAM, OF KANSAS CITY, MISSOURI.

CURTAIN-POLE.

1,308,217.

Specification of Letters Patent.

Patented July 1, 1919.

Application filed May 20, 1918. Serial No. 235,742.

To all whom it may concern:

Be it known that I, THOMAS J. BIGHAM, a citizen of the United States, residing at Kansas City, in the county of Jackson and 5 State of Missouri, have invented certain new and useful Improvements in Curtain-Poles, of which the following is a specification.

This invention relates to curtain poles, and more particularly to extensible poles of this 10 character.

The primary object of the invention is the provision of simple and effective means in connection with a curtain pole for attaching the upper ends or edges of curtains thereto 15 without resorting to the use of rings or pins or fastening means that would be liable to injure the curtains held thereby.

Another object is to provide simple and efficient means for detachably securing the 20 curtain carrying members in operative position in the pole.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made 30 within the scope of what is claimed without departing from the spirit of the invention.

In the accompanying drawings:—

Figure 1 represents a front elevation of a 35 curtain pole constructed in accordance with this invention and shown applied.

Fig. 2 is a bottom plan view of the pole with a curtain engaged therewith shown in section,

Fig. 3 is a longitudinal section through the pole,

Fig. 4 is a transverse section taken on the line 4—4 of Fig. 3, and

Fig. 5 is a similar view taken on the line 45 5—5 of Fig. 3.

In the embodiment illustrated, a tubular sectional pole is shown, the sections 1 and 2 of which are slit longitudinally from end to end to receive curtain retaining elements 50 shown in the form of plates 3 and 4, over which the curtains C are folded and the plates then inserted in the slots of the pole sections as is shown clearly in the drawings.

These plates 3 and 4 each has a dove tailed 55 or undercut notch 5 in one edge which is designed to receive a clamping bolt 6 passed

transversely through each section adjacent its outer end, the nuts of which when tightened, operate to draw the edges of the slot in the section toward each other to clamp the 60 curtain and its plate between said edges (see Fig. 2).

Removable arms in the form of hollow balls 7 are preferably placed on the outer ends of the pole sections, said sections being 65 inserted within the balls as is shown clearly in Fig. 3. The inner meeting ends of the plates 3 and 4 are preferably beveled as shown at 5'.

In the use of this pole, the plates 3 and 4 70 are removed from the pole sections which may be in telescoped position as shown in Figs. 1, 2 and 3 of the drawings, and the upper ends of the curtains to be hung are placed over the notched edges of the plates 75 and said plates then inserted through the slots in the sections into the pole as shown clearly in the drawings. The nuts on the bolts 6 are then tightened up to draw the edges of the slots together and securely 80 clamp the curtains and the plates between them. To remove the curtains, obviously the above described operation will be reversed, the nuts being loosened to permit the removal of the plates through the slots. 85

The foregoing description and the drawings have reference to what may be considered the preferred or approved form of my invention. It is to be understood that I may make such changes in construction and arrangement and combination of parts, materials, dimensions, etc., as may prove expedient and fall within the scope of the claimed invention.

Having thus fully described my invention, what I claim as new and desire to secure by Letters Patent, is:—

1. A tubular curtain pole having a longitudinal slot therein, a plate for insertion through said slot having a notch in one edge, a bolt extending transversely through said pole to draw the edges of the slot toward each other to clamp the plate between them, the notch in said plate fitting around said bolt.

2. A curtain pole composed of tubular telescopically engaged sections having longitudinal slots in their lower faces, bolts extending transversely through said sections in planes at right angles to said slots, plates 110 removably mounted in said sections having undercut notches in their inner edges for

encircling the bolts and their meeting ends beveled.

3. A tubular sectional pole, the sections of which are slotted longitudinally from end to end, plates insertible in said slots and each having an undercut notch in its inner edge, and their meeting ends beveled with their terminals overlapping, and clamping bolts

extending transversely through said sections and positioned to enter said notches.

In testimony whereof I affix my signature in presence of two witnesses.

THOMAS J. BIGHAM.
